UNITED STATES PATENT OFFICE.

CHARLES S. EMERT, OF PEORIA, ILLINOIS.

STRIPPER.

Application filed March 10, 1925. Serial No. 14,515.

My invention relates to machines which are used in conjunction with tamping machines in the formation of concrete blocks and similar products and in which the machine of my present invention is used to raise or force the product out of the mold after it has been tamped or formed therein.

One object of my invention is the provision of a stripper which is power operated and automatic in its action to the extent that when it is set in motion, it completes its stroke and then automatically disengages its driving mechanism and remains at rest until a subsequent operation.

Another object of my invention is the proper protection and lubrication of the mechanism.

Another object of my invention is the provision of a suitable clutch in combination with a yielding device for maintaining its engagement to complete a stroke.

Other objects of my invention will appear and be described in the specification.

The novelty of my invention will be hereinafter more fully set forth and specifically pointed out in the claims.

In the accompanying drawings:—

Fig. 1 sheet 1 is a central sectional side elevation of a machine embodying my invention.

Fig. 2 sheet 2 is a sectional end view of Fig. 1, the section being taken adjacent the right end of the machine and looking to the left.

Fig. 3 sheet 3 is a sectional plan view of Fig. 1, the section being taken about midway between the top and bottom of the machine.

The same numerals of reference are used to indicate identical parts in all the figures.

As illustrating one form of machine embodying my present invention, though without limiting myself to the details of construction or arrangement of parts shown in the drawings and description herein, while availing myself of all variations, modifications, and equivalents which may fall within the scope of the appended claims, I have shown a machine comprising a base 1, upon which a pair of side members 2 are secured, the mold and its associated parts being mounted at the top of these side members and comprising a base member 3 which is somewhat in the form of a grid and which

carries the cores 4, the side plates of the mold being shown at 5 and the ends at 6.

The driving shaft 7 enters the base 1 and as shown more clearly in Figs. 2 and 3 carries a pinion 8 which meshes and drives a gear 9 loosely mounted upon a shaft 10. The shaft 10 is mounted in bearings 11 which extend to the front and back edges of base 1 and are secured thereon as clearly shown in Figs. 2 and 3, these bearings being shown in section in Fig. 1. The shaft 10 carries a crank 12 at each end thereof, these cranks being duplicates and arranged in line and suitably keyed in position to insure their uniform rotation with the shaft 10.

As shown more clearly in Fig. 1 shaft 10 is enlarged as at 13 and the clutch member 14 is feathered upon this shaft and is normally held in the position shown by a coil spring 15 which bears against a thrust collar 16, the latter resting against a small shoulder near the center of the shaft and at one end of the enlarged portion 13. The clutch member 14 carries a pin 17 which is adapted to engage any one of the openings 18 in the gear 9. A clutch shifter 19 is mounted on a shaft 20 and affords means of engaging the pin 17 with one of the holes 18 of the gear 9, the shaft 20 passing through the forward portion of the base and being provided with a treadle 21 which, when depressed rocks the shaft 20 and engages the clutch. Rollers 22 are provided on the upper end of the arms of the shifter 19 to reduce the friction between the parts. The clutch member 14 carries a flange 23 which has two pockets 24 formed in it to receive a roller 25 carried by an arm 26 pivotally mounted as at 27 to one of the bearing members 11, the arm 26 extending to the rear of the machine and embracing a rod 28, the latter being mounted in bearings 29 and 30, and being provided with a fixed collar 31 adjacent the bearing 30. Between the collar 31 and the bearing 29 an expansion spring 32 is mounted, the rod 28 being provided with an adjusting nut 33 which bears against the end of the arm 26 so that this arm is normally held in the position shown in Figs. 1 and 3, though if for any reason, the clutch pin should only partially engage one of the holes in the gear 9, the arm 26 will be forced toward the left compressing the spring 32 and permitting the parts to rotate until such

As shown more clearly in Fig. 1 shaft 10 is enlarged as at 13 and the clutch member 14 is feathered upon this shaft and is normally held in the position shown by a coil spring 15 which bears against a thrust collar 16, the latter resting against a small shoulder near the center of the shaft and at one end of the enlarged portion 13. The clutch member 14 carries a pin 17 which is adapted to engage any one of the openings 18 in the gear 9. A clutch shifter 19 is mounted on a shaft 20 and affords means of engaging the pin 17 with one of the holes 18 of the gear 9, the shaft 20 passing through the forward portion of the base and being provided with a treadle 21 which, when depressed rocks the shaft 20 and engages the clutch. Rollers 22 are provided on the upper end of the arms of the shifter 19 to reduce the friction between the parts. The clutch member 14 carries a flange 23 which has two pockets 24 formed in it to receive a roller 25 carried by an arm 26 pivotally mounted as at 27 to one of the bearing members 11, the arm 26 extending to the rear of the machine and embracing a rod 28, the latter being mounted in bearings 29 and 30, and being provided with a fixed collar 31 adjacent the bearing 30. Between the collar 31 and the bearing 29 an expansion spring 32 is mounted, the rod 28 being provided with an adjusting nut 33 which bears against the end of the arm 26 so that this arm is normally held in the position shown in Figs. 1 and 3, though if for any reason, the clutch pin should only partially engage one of the holes in the gear 9, the arm 26 will be forced toward the left compressing the spring 32 and permitting the parts to rotate until such

As shown more clearly in Fig. 1 shaft 10 is enlarged as at 13 and the clutch member 14 is feathered upon this shaft and is normally held in the position shown by a coil spring 15 which bears against a thrust collar 16, the latter resting against a small shoulder near the center of the shaft and at one end of the enlarged portion 13. The clutch member 14 carries a pin 17 which is adapted to engage any one of the openings 18 in the gear 9. A clutch shifter 19 is mounted on a shaft 20 and affords means of engaging the pin 17 with one of the holes 18 of the gear 9, the shaft 20 passing through the forward portion of the base and being provided with a treadle 21 which, when depressed rocks the shaft 20 and engages the clutch. Rollers 22 are provided on the upper end of the arms of the shifter 19 to reduce the friction between the parts. The clutch member 14 carries a flange 23 which has two pockets 24 formed in it to receive a roller 25 carried by an arm 26 pivotally mounted as at 27 to one of the bearing members 11, the arm 26 extending to the rear of the machine and embracing a rod 28, the latter being mounted in bearings 29 and 30, and being provided with a fixed collar 31 adjacent the bearing 30. Between the collar 31 and the bearing 29 an expansion spring 32 is mounted, the rod 28 being provided with an adjusting nut 33 which bears against the end of the arm 26 so that this arm is normally held in the position shown in Figs. 1 and 3, though if for any reason, the clutch pin should only partially engage one of the holes in the gear 9, the arm 26 will be forced toward the left compressing the spring 32 and permitting the parts to rotate until such

As shown more clearly in Fig. 1 shaft 10 is enlarged as at 13 and the clutch member 14 is feathered upon this shaft and is normally held in the position shown by a coil spring 15 which bears against a thrust collar 16, the latter resting against a small shoulder near the center of the shaft and at one end of the enlarged portion 13. The clutch member 14 carries a pin 17 which is adapted to engage any one of the openings 18 in the gear 9. A clutch shifter 19 is mounted on a shaft 20 and affords means of engaging the pin 17 with one of the holes 18 of the gear 9, the shaft 20 passing through the forward portion of the base and being provided with a treadle 21 which, when depressed rocks the shaft 20 and engages the clutch. Rollers 22 are provided on the upper end of the arms of the shifter 19 to reduce the friction between the parts. The clutch member 14 carries a flange 23 which has two pockets 24 formed in it to receive a roller 25 carried by an arm 26 pivotally mounted as at 27 to one of the bearing members 11, the arm 26 extending to the rear of the machine and embracing a rod 28, the latter being mounted in bearings 29 and 30, and being provided with a fixed collar 31 adjacent the bearing 30. Between the collar 31 and the bearing 29 an expansion spring 32 is mounted, the rod 28 being provided with an adjusting nut 33 which bears against the end of the arm 26 so that this arm is normally held in the position shown in Figs. 1 and 3, though if for any reason, the clutch pin should only partially engage one of the holes in the gear 9, the arm 26 will be forced toward the left compressing the spring 32 and permitting the parts to rotate until such

As shown more clearly in Fig. 1 shaft 10 is enlarged as at 13 and the clutch member 14 is feathered upon this shaft and is normally held in the position shown by a coil spring 15 which bears against a thrust collar 16, the latter resting against a small shoulder near the center of the shaft and at one end of the enlarged portion 13. The clutch member 14 carries a pin 17 which is adapted to engage any one of the openings 18 in the gear 9. A clutch shifter 19 is mounted on a shaft 20 and affords means of engaging the pin 17 with one of the holes 18 of the gear 9, the shaft 20 passing through the forward portion of the base and being provided with a treadle 21 which, when depressed rocks the shaft 20 and engages the clutch. Rollers 22 are provided on the upper end of the arms of the shifter 19 to reduce the friction between the parts. The clutch member 14 carries a flange 23 which has two pockets 24 formed in it to receive a roller 25 carried by an arm 26 pivotally mounted as at 27 to one of the bearing members 11, the arm 26 extending to the rear of the machine and embracing a rod 28, the latter being mounted in bearings 29 and 30, and being provided with a fixed collar 31 adjacent the bearing 30. Between the collar 31 and the bearing 29 an expansion spring 32 is mounted, the rod 28 being provided with an adjusting nut 33 which bears against the end of the arm 26 so that this arm is normally held in the position shown in Figs. 1 and 3, though if for any reason, the clutch pin should only partially engage one of the holes in the gear 9, the arm 26 will be forced toward the left compressing the spring 32 and permitting the parts to rotate until such

As shown more clearly in Fig. 1 shaft 10 is enlarged as at 13 and the clutch member 14 is feathered upon this shaft and is normally held in the position shown by a coil spring 15 which bears against a thrust collar 16, the latter resting against a small shoulder near the center of the shaft and at one end of the enlarged portion 13. The clutch member 14 carries a pin 17 which is adapted to engage any one of the openings 18 in the gear 9. A clutch shifter 19 is mounted on a shaft 20 and affords means of engaging the pin 17 with one of the holes 18 of the gear 9, the shaft 20 passing through the forward portion of the base and being provided with a treadle 21 which, when depressed rocks the shaft 20 and engages the clutch. Rollers 22 are provided on the upper end of the arms of the shifter 19 to reduce the friction between the parts. The clutch member 14 carries a flange 23 which has two pockets 24 formed in it to receive a roller 25 carried by an arm 26 pivotally mounted as at 27 to one of the bearing members 11, the arm 26 extending to the rear of the machine and embracing a rod 28, the latter being mounted in bearings 29 and 30, and being provided with a fixed collar 31 adjacent the bearing 30. Between the collar 31 and the bearing 29 an expansion spring 32 is mounted, the rod 28 being provided with an adjusting nut 33 which bears against the end of the arm 26 so that this arm is normally held in the position shown in Figs. 1 and 3, though if for any reason, the clutch pin should only partially engage one of the holes in the gear 9, the arm 26 will be forced toward the left compressing the spring 32 and permitting the parts to rotate until such

time as the pin either become fully engaged with the gear or the next pocket 24 comes opposite the roller 25, whereupon the spring 32 would return the roller to the position of Fig. 3.

The spring 32 and its leverage as applied to the roller 25 is considerably stronger than the spring 15 and would overcome the latter on occasions when any interfering action between the two springs might be established.

The cranks 12 carry connecting rods 34 and these connecting rods engage a shaft 35 which carries a pair of cross-heads 36, one at each side of the machine and guided by ways 37 formed in the side plates 2.

Each cross-head 36 carries a pair of rods 38 which extend upward through suitable bearings 39 in a roof-shaped cross member 40, the upper ends of the rods 38 engage the stripping member 41 which normally lies within channels formed by the grids of the member 3, the shape of the member 41 is such that it will freely pass up and down within the mold as the shaft 10 rotates.

Some of the grid members which form the member 3 are provided with projecting ribs 42 which terminate at the upper surface at the member 3 and upon which the platen 43 rests, the platen being shaped to nearly fit the pocket portion of the mold, and being preferably made of comparatively thin metal such as sheet metal or malleable casting.

The gear 9 carries an eccentric 44 (Fig. 1) and a pump comprising a cylinder 42^a and a piston 43^a is mounted so that the piston is operated by the eccentric 44 when the gear 9 rotates, the machine being made so that the base will hold a quantity of lubricating oil, the pump being provided with a suction element 44^a, Fig. 2 and a discharge pipe 45 which leads, as shown in Fig. 1, to the side of the machine and upward and then to the center and is connected to a distributor 46.

The distributor 46 comprises a horizontal trough portion which terminates at each end in a pair of angularly arranged troughs which extend to and embrace the rods 38 a short distance below the bearing 39 and between these bearings and the terminations of the angularly arranged troughs, absorbent washers 47 are mounted which not only serve to distribute the lubricant on the rods 38 but also to keep these rods in a clean condition. Lateral branches 48 extend from the distributor 46 and terminate to distribute a portion of the oil onto the ways 37 of the cross-heads 36. Small holes 49 are drilled in the distributor to divert a portion of the oil and drop it upon the shaft 35 from which the oil in turn drops upon clutch mechanism and roller and other parts, before described, as will be readily apparent.

The operation of the machine is as follows:

Assuming that the parts are all assembled as shown in the drawings and the machine is in place and connected so that power may be applied to the shaft 7, and a platen is in place within the mold. The mold is filled with concrete or other material from which the block or other product is to be made, and the material properly tamped and the upper surface of the block struck off, the operator presses the pedal 21 downward and thereby engages the pin 17 with one of the holes 18 of the gear 9. As soon as the clutch is thus engaged the operator can lift his foot from the pedal and the machine will continue its stroke until the shaft 10 has made a half revolution which will raise the platen and the block to a point slightly above the top surface of the mould so that the platen and block may be removed for curing. When the shaft 10 has made a half revolution, the next pocket 24 comes opposite the roller 25 and the spring 15 causes the disengagement of the clutch and the consequent stopping of the shaft, the engagement of the roller 25 with the pocket 24 affording a sufficient lock to hold the parts of the machine against accidental movement.

After the block and platen have been removed a new platen is placed upon the stripping plate 42 and the pedal 21 again pushed downward. This again causes the engagement of the clutch and the shaft 10 makes another half revolution, lower the platen to the proper place for the formation of the next block and places the parts again in the position shown in the drawings. Meanwhile the gear 9 is continuously rotating and its eccentric is constantly operating the pump to supply oil to the distributor 46 to lubricate all the parts of the machine which do not dip into the oil in the base 1.

It might sometimes happen that in causing the engagement of the clutch, and especially after the edges of the holes become worn, the gear might start to rotate the clutch member before the pin 17 is fully engaged and to prevent injury to the parts, the yielding mounting for the roller 25 is provided so that upon partial engagement of the pin 17 the clutch 14 can make its half revolution or if the lead is great enough to cause the pin to slip out of its partial engagement, the pin will be held tightly against the face of the gear until the next hole comes opposite it, whereupon the spring 32 will snap the pin into engagement to complete the half revolution of the shaft.

As shown more clearly in Fig. 2, front and rear plates 50 are attached to the machine to complete the enclosure of the mechanism to exclude dust or concrete or other foreign matters from the interior of the machine and to keep the oil in proper condition.

When it is desired to change from one

size or shape of block to another, the grid element 3 and the parts which it carries, are removed from the top of the machine and a new equipment having the proper mold arrangement is substituted. Such a change would be required in changing from concrete blocks to concrete bricks or from one style of block to another.

A machine built as herein shown and described is comparatively simple and easy to construct and assemble and is exceedingly efficient in action, operates without jar or noise and starts its stripping action at a slow rate of speed, accelerates toward the center of the stroke and slows down as it reaches the upper end of the stroke so that the block is raised from the machine without damage, or crushing it, or injuring it in any way and leaving the operator's hands free for other duties during the time the machine operates.

Having thus fully described my invention I claim:

1. In a stripper the combination of a frame, a mold carried thereby, a stripping member movable within the mold, a crank shaft and connections for moving the stripping member, power operated driving mechanism for the crank shaft, and clutch connections between the power operated driving mechanism and the crank shaft whereby when the clutch is engaged the crankshaft will be rotated to impart one stroke to the stripping member and then the clutch will be disengaged.

2. In a stripper the combination of a frame, a mold carried thereby, a stripping member mounted for movement within the mold, a crank shaft, reciprocating cross-heads moved by the crank shaft, rods between the cross-heads and the stripping member, a driving member loosely mounted on the crank shaft, a clutch between the driving member and the crank shaft, means for engaging the clutch, and means for maintaining the clutch in engagement until the completion of a stroke of the stripping member.

3. In a stripper the combination of a frame, a mold carried thereby, a stripping member movable in the mold, a power operated driving means for the machine, a clutch for connecting the power means to move the stripping member, and means for maintaining the clutch in engagement until the completion of a stroke of the stripping member.

4. In a stripper the combination of a frame, a mold carried thereby, a stripping member movable in the mold, a power operated driving means for the machine, a clutch for connecting the power means to move the stripping member, and yielding means for maintaining the clutch in engagement until the completion of a stroke of the stripping member.

5. In a stripper the combination of a frame, a mold carried thereby, a stripping member movable in the mold, a power operated driving means for the machine, a clutch for connecting the power means to move the stripping member, and yielding means for maintaining the clutch in engagement until the completion of a stroke of the stripping member, said yielding means holding the parts in proper relation until the next engagement of the clutch.

6. In a stripper the combination of a frame, a mold carried thereby, a stripping member movable within the mould, power operated driving mechanism mounted in the frame and for moving the stripping member, a housing over the driving mechanism for excluding foreign matters and to retain lubricant, reciprocating rods moved by the driving mechanism and passing through the housing to move the stripping member, a crank shaft, connections between the crank shaft and the reciprocating rods, intermittently movable driving connections for the crank shaft, a means for maintaining the engagement of the driving connections until the completion of a stroke of the stripping member and then causing the disengagement of the driving connections.

CHARLES S. EMERT.
